UNITED STATES PATENT OFFICE.

JOSEPH NESTER, OF WAPAKONETA, OHIO.

HORSESHOE.

SPECIFICATION forming part of Letters Patent No. 280,658, dated July 3, 1883.

Application filed May 26, 1883. (No model.)

To all whom it may concern:

Be it known that I, JOSEPH NESTER, a citizen of the United States, resident at Wapakoneta, in the county of Auglaize and State of Ohio, have invented certain new and useful Improvements in Horseshoes; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention in a perspective view. Fig. 2 is a side view. Fig. 3 is a vertical section. Fig. 4 is a top view.

This invention has relation to spring-heel horseshoes; and it consists in the construction and novel arrangement of the bifurcated heel branches of the shoe, whereof the outer portions are short and level to sustain the rim of the hoof, and the inner depressed spring portions are long and formed with outwardly-turned offsets at their bearing ends, said offsets being in rear of the ends of the shorter portions and protecting the heel of the animal, all as hereinafter set forth.

In the accompanying drawings, the letter *a* designates the front portion of the horseshoe, and *b b* the heel branches, which are bifurcated from about the middle of each branch toward the rear. An angular cut, *c*, is made to separate the short outer or rim portion, *d*, from

the longer inner or spring portion, *e*, which 35 extends back of the rim portion *d*, and is formed with an outwardly-turned offset, *g*, in rear of the end of the rim portion *d*, and forming a broad bearing end for the spring *e*. The spring portions *e* are depressed below the 40 rim portions, and are properly tempered. The rim portions *d* are level with the arch *a* of the shoe, and are designed to fit closely to the rim of the hoof, protecting its heel portion fully to the end thereof. The inner spring-arms, *e*, 45 being widened at their ends by the offsets, form broad bearings, protecting the tender extremities of the heel. In this construction it will be observed that the tendency of the shoe is to allow the heel portions of the hoof to 50 spread.

Having described this invention, what I claim, and desire to secure by Letters Patent, is—

A spring-heel horseshoe having a short 55 outer arm of its bifurcated branch, designed to fit closely to the rim of the heel portion of the hoof, and the long inner depressed spring-arm outwardly offset at its end to provide a broad terminal bearing in rear of and protecting the extremity of the heel, substantially as specified.

In testimony whereof I affix my signature in presence of two witnesses.

JOSEPH NESTER.
